[57] CLAIM

The ornamental design for an electrically powered ceiling fan motor housing, as shown and described.

DESCRIPTION

FIG. 1 is a bottom and side perspective view of an electrically powered electric ceiling fan motor housing showing my new design;

FIG. 2 is a side elevation view thereof, the other three sides being identical to that shown;

FIG. 3 is a bottom plan view thereof; and,

FIG. 4 is a top plan view thereof.

The broken line showing of fan blades in FIGS. 1-4 is for illustrative purposes only, and forms no part of the claimed design.

FIG. 1

FIG. 2

FIG. 3
